V. H. ENGLAND

SPRING COMPRESSING MECHANISM

Filed Jan. 3, 1922

Patented Feb. 3, 1925.

1,525,174

UNITED STATES PATENT OFFICE.

VICTOR H. ENGLAND, OF DENVER, COLORADO;

SPRING-COMPRESSING MECHANISM.

Application filed January 3, 1922. Serial No. 526,628.

To all whom it may concern:

Be it known that I, VICTOR H. ENGLAND, a citizen of the United States, and a resident of the city and county of Denver, State of Colorado, have invented certain new and useful Improvements in Spring-Compressing Mechanism, of which the following is a description; reference being had to the accompanying drawings, forming a part here-

of.

The object of the invention is to provide means for readily compressing springs and maintaining the compression during handling.

The invention relates more particularly to devices for so compressing and handling valve springs, clutch springs and the like during engine repairs, but is adaptable to use on other springs.

Briefly the invention comprises an extensible device in the form of two members having spring engaging jaws, and means, preferably carried by one of said members, for clamping the two together in adjusted relation. In order that an extra long spring or an unusually stiff spring may be compressed and handled, a pair of heads having seats for the ends of the spring are employed, these heads being adapted to be placed in a vise or the like for compression of the spring and having notches in their edges for receiving the jaws of the extensible retaining device, whereby the compressed spring may be readily transferred from the vise and handled.

In the drawings wherein certain embodiments of the invention are disclosed,

Fig. 1 is a perspective view showing the extensible compressing and retaining device partially extended;

Fig. 2 is a plan thereof showing a slightly modified form of clamp;

Fig. 3 is a longitudinal section taken on the line 3—3 of Fig. 2;

Fig. 4 is a transverse section taken on line 4—4 of Fig. 1;

Figs. 5 and 6 are face and edge elevations respectively of the notched spring engaging heads as indicated by lines 5—5 and 6—6;

Fig. 7 is an elevation indicating the manner of use of said heads.

The compressing and retaining device comprises two slidably connected members 10 and 12, the member 10 having two spaced rails connected by a head or spring engag-

ing jaw 14. The member 12 is in the form of a tongue slidably mounted between the rails 10 and having a spring engaging jaw 15. The slidable connection between these members is had by a tongue and groove connection comprising beveled tongues 16 on the rails 10 and corresponding grooves 18 in the tongue or shank 12 of the other member.

The members are clamped together by means of a bar 20 integral with one rail 10 and extending under the tongue 12 to a point beyond the other rail whereby it is provided with a lug 22 lying alongside said other rail. In the form shown in Figs. 1 and 4, lug 22 carries a thumb screw 24 for forcing the adjacent rail 10 against the tongue 12 to bind the parts. In the form of Fig. 2 a cam 25 is eccentrically mounted in a groove in the lug 22, this cam being operable by a lever 26 and thereby movable into binding engagement with the rail. The inner end of member 12 carries a projecting stop 28 adapted to engage against the bar 20 to prevent the members from being separated as by a compressed spring or otherwise.

In the use of this device, the members are extended, a spring placed between the jaws 14 and 15, pressure placed upon the jaws 14 and 15 to compress the spring S, and the clamping element 24 or 25 operated to bind the parts for retaining the spring in compressed relation.

In the event that the spring S is too long for the device, or too stiff for easy compression, the same may be placed between a pair of heads 30 having one or more notches 32 in their edges for the purpose of receiving the jaws 14 and 15. These heads carry frusto-conical or similar bosses 34 for seating the ends of the spring and are of such size as to accommodate various spring sizes. When the heads 30 are placed between the jaws V of a vise or the like, the bosses 34 retain the ends of the spring during compression. The jaws 14 and 15 are then placed in the notches 32 and in engagement with the ends of the spring, and the clamp set. Release of the jaws V of the vise leaves the compressed spring between the jaws 14 and 15 of the compressing and retaining device 10, 12. The friction between the edges of the rails 10 and tongue 12 and the walls of the tongue and groove connection 16, 18 is ample to retain the parts

even under the tension of the compressed spring S, when the clamp is set.

By means of the construction herein disclosed, a spring may be readily compressed 5 and held in compressed condition for placing in position on the engine, clutch or other part. Preferably a compressing device of this invention will ordinarily be placed at each side of the spring to be retained.

10 I claim:

1. A spring compressor having a pair of relatively movable members provided with spring engaging jaws, one member having a pair of spaced side rails on which the respective jaw is mounted, and the other member having a tongue slidably mounted in and between said rails, and means for clamping the tongue between the rails, said means projecting laterally from one 15 side of the device at the outer side of one of the rails.

2. A spring compressor comprising a pair of members having spring engaging jaws, one member having a pair of spaced rails 20 and the other member having a tongue slidably mounted between said rails, and a clamping device carried by one rail and engaging the other rail to compress the same against said tongue.

30 3. A spring compressor comprising a pair of members having spring engaging jaws, one member having spaced rails and the other member having a tongue slidably mounted between said rails, a clamping device carried by one rail for engaging and compressing the other, and a stop carried by 35 said tongue to engage against said clamping device to prevent separation of the members.

4. In combination, a pair of heads having 40 seats for the ends of a spring, and a pair of slidable members having jaws, said jaws also being adapted to engage the ends of the spring carried by said heads, said members having means to lock them together to retain 45 the spring between them, said heads being separate from said members and adapted to be placed in a vise with the spring therebetween for compression of the spring.

5. In combination, a pair of heads having 50 seats for the ends of a spring held between them, each head having a notch in the side thereof, and a pair of slidably connected members having spring engaging jaws adapted to be received in said notches for 55 engagement with the ends of the spring held by said heads, and means to clamp said members together to retain the spring.

6. In combination, a pair of heads having seats for the ends of a spring held between 60 them, each head having a notch in the side thereof, and a spring retainer having spring engaging jaws adapted to enter said notches to engage the ends of the spring.

7. A spring compressing device comprising 65 a pair of members each of which has a spring engaging jaw at one end, one member having a pair of spaced rails and the other member having a tongue slidably mounted between said rails, and a clamping device 70 carried by one rail and projecting laterally from the opposite side of the compressing device beyond the other rail and engaging said other rail to compress the same against the tongue.

In testimony whereof I affix my signature.

VICTOR H. ENGLAND.
